UNITED STATES PATENT OFFICE

EDWARD BRUNHOFF, OF WYOMING, OHIO, ASSIGNOR TO THE ARNOLD ELECTRIC COMPANY, OF RACINE, WISCONSIN, A CORPORATION OF WISCONSIN

DISPENSING APPARATUS

Application filed April 15, 1927. Serial No. 184,126.

My invention relates to improvements in dispensing apparatus. One of its objects is to provide improved apparatus adapted to display pulverous substances, as for instance 5 malted-milk or chocolate, for sale and to dispense or deliver the same in substantially uniform measured quantities by lever actuated dispensing mechanism. Another object is to provide an improved assembly and 10 combination of apparatus for such purpose. Another object is to provide dispensing apparatus adapted to be readily separated into its components so as to be immersed in warm or hot water for cleaning purposes, and to 15 be conveniently assembled. Another object is to provide improved coupling means for coupling the measuring and dispensing mechanism with the actuating mechanism. Another object is to provide improved actuating 20 mechanism actuated by a downward movement of the actuating lever and adapted to move uniformly at a predetermined step by step movement to insure uniform measurement and delivery. Another object is to provide improved lever actuated ratchet 25 mechanism. My invention also comprises certain details of form and arrangement and combination of components, all of which will be fully set forth in the description of the 30 accompanying drawings, in which:

Fig. 1 is a perspective view of a dispensing apparatus embodying my improvements.

Fig. 2 is a perspective view of the dispensing tray, detached.

Fig. 3 is a perspective view of the dispensing tray, detached and inverted.

Fig. 4 is a perspective view of a diaphragm or separator interposed between the body of the article to be dispensed and the exit or delivery port, detached.

Fig. 5 is a plan of the dispensing apparatus shown in Fig. 1 with the lid and hopper or container cylinder detached.

Fig. 6 is a perspective view of the measuring and dispensing member detached.

Fig. 7 is a perspective view of a combined coupling member and power agitating member detached.

Fig. 8 is a view similar to Fig. 6 illustrating a modification thereof.

Fig. 9 is a view similar to Fig. 7, illustrating a modification thereof.

Fig. 10 is a plan of the ratchet mechanism and lever mechanism employed to actuate the dispensing apparatus.

Fig. 11 is a sectional detail taken upon line 11—11 of Fig. 10.

Fig. 12 is a perspective view of the feeding ratchet wheel detached.

Fig. 13 is a side elevation of the actuating lever detached.

Fig. 14 is a perspective view of a pawl carrying rocker plate detached.

Fig. 15 is a perspective view of a pawl detached.

The accompanying drawings illustrate what are believed to be the preferred embodiments of my invention. As illustrated in the principal figures 18 represents a base or support in the upper end of which is 70

formed a chamber 19, in which are mounted an actuating lever 20, ratchet wheel 21, and other apparatus required to actuate the measuring and dispensing apparatus. Detachably mounted upon the upper end of the 75

base 18 and forming a lid for the chamber 19 is a dispensing tray 22 provided with a raised annular rim 23, and provided with an exit or delivery port 24, through the 80

floor thereof near the rim 23 at one side of its center, and a central perforation 25 for the passage of a key or driving axle 26. A 85

tubular member 27, preferably of transparent material is seated within the upper portion of the rim 23, with its lower edge resting upon a ledge 28 formed part way down the inner face of the rim 23 by increasing the thickness of the lower portion of the rim 23.

The tubular member 27 and tray 22 form a container for the pulverous material to be 90

dispensed. A cap or lid 29 is detachably seated upon the upper edge of the tubular member 27. The material to be dispensed is charged in bulk into the container or hopper 27, where it is exposed to view through the transparent walls of the member 27, and at the same time is housed and protected 95

against dust or moisture.

Resting loosely upon the floor of the tray 22 is a dispensing spider comprising a cen- 100

tral hub 30 and an annular body or core 31, from which a series of arms 32 extend radially until their free ends come close to the inner face of the lower portion of the rim 23, thereby practically centering the dispensing spider within the tray 22. The hub 30 extends a short distance above the upper face of the core 31, thereby forming an annular shoulder or bearing 33. The hub 30 is also provided with a polygonal perforation 34, or an equivalent thereof, to prevent the axle or key rotating relative to said hub. A diaphragm plate 35, see Fig. 4, has a perforation 36 to register with and form a bearing for the shoulder 33 of the hub 30. One section 37 of the plate 35 rests flat upon the upper face of the body or core 31, while the other section 38 rests upon at least two of the radial arms 32 directly above the exit port 24, so as to prevent the material to be dispensed from being discharged directly from the hopper downwardly between the radial arms 32 and through the exit port without measuring and controlling the feed thereof. The outer edge 39 of the section 38 enters an off-set or recess 40 in the ledge 28 to lock or retain the plate 35 in place at one end thereof, while the bearing 33 retains the opposite end of plate 35 in place while in operation. The lower edge of the tubular member 27 bears upon the upper face of the plate 35 at its outer edge 39 to hold the edge 39 in place in the recess 40. At the same time the plate 35 and dispensing spider may be readily lifted out and washed or dipped in hot water and dried and returned to their operative positions. The edge 39 of section 38 is preferably beveled as shown in Fig. 5.

The actuating lever 20 is pivotally attached at 42 to a projection 43 extending inwardly from the wall of chamber 19. The arm 44 of lever 20 rocks on the center 42, and has pivotally attached thereto at one end a link 45. The arm 46 of lever 20 extends from the interior of chamber 19 through a slot 47 to the exterior of the base, where it is provided with a head or push-button 48. The lever 20 is actuated by pressure downwardly upon the head 48, which is in a direction 50 which has the least tendency to upset or disturb the equilibrium of the apparatus.

Inside the chamber 19 are two triangular frame members 50 and 51, one below the other, which are attached together at their extremities, and also attached rigidly to ears 52 projecting inwardly from the walls of chamber 19, by means of screws 53. The ratchet wheel 21 has a series of uniformly spaced ratchet teeth 55, and a polygonal bore 56 corresponding to the exterior of the driving shaft 26. The hub 57 of the ratchet wheel journals in a bearing in the upper frame member 50, and the hub 58 of the ratchet wheel journals in a bearing in the lower frame member 51, thus holding the ratchet wheel

journalized in chamber 19 with its axis of rotation in a substantially vertical position and directly beneath the bore 34 of the spider. The dispensing tray is provided upon its under face with dowel pins 59 which register with and enter perforations 60 in the lugs 61 projecting from the walls of the chamber 19 inwardly, thus automatically centering the tray 22 upon the base 18, to close the chamber 19, and enabling the tray 22 and all parts carried thereby to be freely lifted away from the base 18, and replaced thereon.

A rocker plate 63 is journalized upon the hub 58 of the ratchet wheel 21 above the frame member 51, and is pivotally attached to the opposite end of the link 45 by means of a screw or pin entering the perforation 64 of said plate 63, thereby causing the plate 63 to rock to and fro when the lever 20 is actuated. A pawl 65 is pivotally attached to the plate 63 by means of a screw or pin entering the perforation 66, and the free end of said pawl is held yieldingly in engagement with the ratchet teeth 55 by means of a leaf spring 67 held rigidly at one end in a slot in the lug 68 projecting upwardly from the plate 63. The pawl 65 as shown is set to rotate the ratchet wheel 21 in a clock-wise direction. A pawl 70 is pivotally attached to the upper frame member 50 at 71, and is provided with a transverse pin 72 extending above and below said pawl. The free end of pawl 70 engages the teeth 55 of the ratchet wheel 21 to limit the movement of the ratchet wheel to a single clock-wise step at a time, which is effected through the upper end of the pin 72 having a limited movement between the edge of the frame member 50 and a finger 73 projecting outwardly from the side of the frame member 50, while at the same time the lower end of the pin 72 projects into a space between the cam members 74 and 75 extending outwardly from the rocker plate 63, to cause the pawl 70 to be lifted out of the path of the teeth 55 by the cam 75 when the lever 46 is released or elevated, and the pawl 65 is retracted for a new engagement and to force the pawl 70 into the path of a tooth 55 due to engagement of the cam 74 with pin 72 at the end of the forward movement of the pawl 65 and plate 63, due to depression of the lever 46. Thus the ratchet wheel 21 at each depression of the lever 46 makes a uniform forward feed equal to the space from one tooth 55 to the next, and due to the cams 74 and 75 and pin 72 does not make a partial or incomplete throw or feed of the ratchet wheel. A coiled spring 78 serves to return and hold the lever 46 in elevated position ready to be depressed.

After the tray 22 has been placed in position upon the chamber 19 of the base, the dispensing spider is placed upon the floor of the tray 22, and the plate 35 placed in position. The driving shaft or axle 26 is then inserted through the polygonal perforation 34 in the

spider and down through the perforation 25 of the tray and into the polygonal perforation 56 in the ratchet wheel 21, thereby coupling the spider in driving relation to the ratchet wheel, and at the same time enabling the driving shaft to be freely inserted or lifted out as required. At the upper end of the shaft 26 is a cross bar 95 which extends above the plate 35 into the material to be dispensed, and serves to agitate the lower portion thereof so as to insure feeding of the material to be dispensed uniformly into the spaces between the arms 32 of the spider and thereby a uniform measuring of the material to be dispensed.

It will be noted that in Figs. 5, 6 and 7 there are eight radial arms 32, and that the key or shaft 26 is square in cross section, which results in so coupling the spider relative to the ratchet wheel as in each instance to place the exit port 24 between two of the arms 32 each time that the spider and ratchet wheel come to a position of rest, which position is important to a proper operation of the apparatus. In Figs. 8 and 9 I have illustrated a modification in which the spider 80 is provided with six arms 81, in place of eight arms as shown in Fig. 6. In Fig. 8 the bore 82 is hexagonal, and in Fig. 9 the shaft 84 is hexagonal instead of square as in Fig. 7. Also a ratchet wheel having a hexagonal bore to register with the shaft 84 would be employed with the spider and shaft of Figs. 8 and 9, in order to insure spacing of two of the arms 81 upon opposite sides of the exit port 24 each time that the ratchet wheel and spider reached a position of rest.

At the upper end of the shaft 26 is a disk 86 which in operation lies flush upon the upper face of the plates 35 in such relation thereto as to prevent any of the material to be vended from working or getting into the bore 34 of the spider and to thereby prevent any of the material to be vended reaching the operative parts within the chamber 19.

Some of the materials designed to be dispensed through my improved apparatus contain sugar or similar material having a tendency to take up moisture and to adhere to the faces of the operative parts, and in any event it is important to be able to keep these parts clean and in sanitary condition. All of the parts of my improved apparatus which come into contact with the material to be vended are adapted to be readily separated one from another without the use of bolts or screws or similar fastening members, and to be washed, heated and sterilized and then as readily reassembled for use, and the structure is such that the parts are incapable of being assembled in inoperative or improper relation.

The operation is as follows; the tray 22 is placed in position above the chamber 19, being guided to position and retained therein by the dowel pins 59. The spider 31 and

plate 35 are placed within the tray 22, and the key or shaft 26 inserted from above through the bore 34 in the spider and into the bore 56 in the ratchet wheel. The tubular member 27 is then placed in position to rest upon the ledge 28 and to prevent displacement of the plate 35. The powder to be dispensed is then filled into the member 27 and the lid 29 placed in position. Thereafter each operation of the lever 20 causes the ratchet wheel to move one step forward clock-wise, carrying with it the spider 31 and its arms 32 together with the powder located between the respective arms 32. Each movement of the spider carries one of the arms across the exit port 24, and causes the powder between two of said arms 32 to be fed beneath the section 38 of plate 35, and hence to be discharged through the exit port 24 into a container held below the exit port 24. As soon as the lever 20 is released, the same is returned to its normal position, carrying with it the rocker plate 63, which resets the ratchets ready for a new operation. Each movement of the spider carries the shaft 26 and its cross arm 95 therewith, causing the arm 95 to agitate the powder above the plate 35 and above the spider to thereby feed the powder from above down into the spaces between the arms 32, until each of said spaces is uniformly filled so long as there is a supply of powder above to be fed thereto.

In order to insure invariable discharge of the powder from between the arms of the spider and through the exit or delivery port 24, I preferably provide arms 32 or 81, which are thicker at their upper edges than at their lower edges, as shown in Figs. 6 and 8, to thereby provide downwardly diverging pockets between the arms 32 or 81 to more readily detach and discharge the powder through the exit port 24. To further insure such invariable discharge of the powder, I preferably provide a recess 98 upon the under face of the plate 38 and vertically above the exit port 24. In this recess 98 is mounted along one edge a leaf spring 96 of thin spring sheet metal, which yields and enters the recess 98 to permit the passage of the respective arms 32 or 81, and which is released so as to spring or press downwardly upon the powder in the pocket between any two arms 32, as soon as the advanced arm 32 of the pair has passed out of engagement with the free end of the spring 96.

The apparatus herein shown and described is capable of considerable modification within the scope of the claims without departing from the spirit of my invention.

What I claim is:

1. A dispensing apparatus comprising a base, actuating mechanism including a rotary member having a non-circular bore mounted in said base, a dispensing tray detachably mounted upon said base and form-

ing the bottom of a dispensing hopper, a dispensing member having a non-circular bore mounted in the bottom of said tray and adapted when actuated to dispense the contents of said hopper in measured quantities, and an actuating shaft having a cross-section fitting said bores and a powder excluding head, said shaft adapted to be freely inserted endwise from within said hopper to 10 operatively connect said dispensing member to the actuating mechanism in said base, and to exclude powder from said actuating mechanism.

2. A dispensing mechanism comprising a base, an actuating mechanism having a ratchet with a polygonal bore therein and an actuating lever movable in a substantially vertical direction, a dispensing tray detachably mounted upon said base and forming the bottom of a dispensing hopper, a dispensing member having a polygonal bore mounted detachably in the bottom of said tray and adapted when actuated to dispense the contents of said hopper in measured quantities, and an actuating shaft fitting the bores of said ratchet and dispensing member and having a powder excluding head and freely movable endwise and detachably from within said tray through the bottom of said tray to operatively connect said dispensing member to said actuating mechanism, and to exclude powder from said actuating mechanism.

3. A dispensing apparatus comprising a base, an actuating mechanism mounted in said base and having a ratchet wheel mounted rotatably upon a substantially vertical tubular axle having a non-circular bore, a dispensing tray detachably mounted upon said base above said actuating mechanism and forming the bottom of a dispensing hopper, a dispensing member having a hub portion with a non-circular bore and detachably and rotatably mounted in the bottom of said tray and adapted when actuated to dispense the contents of said hopper in measured quantities, and an actuating shaft having a non-circular cross section fitting said bores and a powder excluding head, said shaft adapted to be detachably and freely inserted endwise through the bottom of said tray to operatively connect said dispensing member with the axle of said actuating mechanism ratchet wheel.

4. A dispensing apparatus comprising a dispensing tray forming the bottom of a dispensing hopper, said tray having a dispensing port, a dispensing member having an axial, non-circular bore located in said tray and operable to discharge the contents of said hopper in measured units through said dispensing port, a base supporting said hopper and tray, an actuating lever adapted to move in a substantially vertical direction when actuated, a ratchet wheel journaled upon a vertical axis and provided with a non-circu-

lar axial bore, a rocker plate journaled concentrically with the axle of said ratchet wheel and connected to and adapted to be reciprocated by said actuating lever, an actuating pawl carried by said rocker plate and adapted to feed said ratchet wheel forward step by step, a stop pawl faced in a reverse direction to that of said actuating pawl, and adapted to engage the teeth of said ratchet wheel to prevent said ratchet wheel moving except in a predetermined manner, and means to positively actuate said stop pawl to permit said ratchet wheel to move only one step at a time, and an actuating shaft having a cross-section fitting said bores in the dispensing member and ratchet wheel adapted to be freely and detachably inserted endwise therein to operatively connect said dispensing member and ratchet wheel.

5. A dispensing apparatus comprising a base member, an actuating member having a non-circular bore mounted upon said base member, a dispensing tray provided with a dispensing port detachably and loosely mounted upon said base member, interengaging dowel members to guide and hold said tray relative to said base member, a dispensing member having a non-circular bore and provided with powder receiving measuring pockets detachably mounted upon the floor of said tray and adapted to feed the contents of the tray to said dispensing port, and a connecting member fitting the bores of and freely insertable axially of said dispensing and actuating members to operatively and detachably connect said members.

6. A dispensing apparatus comprising a base member, an actuating mechanism, including a ratchet having a non-circular bore, mounted upon said base member and provided with a downwardly movable actuating lever serving when actuated to stabilize said base member, a dispensing tray provided with a dispensing port detachably and loosely mounted upon said base member, interengaging dowel members carried by said base member and said tray to guide and hold said tray relative to said base member, a dispensing member having a non-circular bore and provided with powder receiving and measuring pockets detachably and loosely mounted upon the floor of said tray and adapted to feed the contents of the tray to said dispensing port, and a connecting member fitting said non-circular bores and adapted to be freely and detachably inserted from above axially of said dispensing member to operatively and detachably connect said dispensing member to said ratchet.

7. Dispensing apparatus comprising a base member, actuating mechanism mounted in said base member, dispensing apparatus separably mounted upon said base member, a coupling stem adapted to be detachably inserted from above and to couple said dispens-

ing apparatus operatively to said actuating mechanism, and a manually operable actuating lever operable by pressure downwardly thereon in a substantially vertical direction, said actuating mechanism and dispensing mechanism having aligned non-circular apertures through which said coupling stem may be inserted.

8. Dispensing apparatus comprising a base member, actuating mechanism mounted in said base member, a dispensing tray mounted separably upon and above said base and actuating mechanism and provided with a dispensing port in the floor thereof, a dispensing spider mounted loosely upon the floor of said tray and provided with an upwardly extending centrally located shoulder, a plate mounted non-rotatably relative to said tray vertically above said dispensing port and above said dispensing spider, a coupling stem provided with a head recessed to fit over the raised central shoulder of said dispensing spider and detachably insertable from above and serving to operatively couple said dispensing spider to said actuating mechanism.

9. Dispensing apparatus comprising a base member, actuating mechanism mounted in said base member, a manually operable actuating lever operable by pressure downwardly thereon in a substantially vertical direction, a dispensing tray separably mounted upon and above said base member and actuating mechanism and held and guided into position relative to said base member by means of a vertical dowel pin, said dispensing tray being provided with a dispensing port, a dispensing spider mounted within said dispensing tray, a plate above said dispensing port and above said dispensing spider, and upwardly removable means for detachably coupling said spider with said actuating mechanism.

In testimony whereof I have affixed my signature.

EDWARD BRUNHOFF.
